UNITED STATES PATENT OFFICE.

WINTHROP L. JACOBS, OF EAST ORANGE, NEW JERSEY, ASSIGNOR TO THE
HARTFORD CARPET COMPANY, OF HARTFORD, CONNECTICUT.

DESIGN FOR A CARPET.

SPECIFICATION forming part of Design No. 13,379, dated October 31, 1882.

Application filed August 11, 1882. Term of patent 3½ years.

To all whom it may concern:

Be it known that I, WINTHROP L. JACOBS, of East Orange, in the State of New Jersey, have invented a new and original Design for Carpets, of which the following is a specification.

This invention relates to a new and original design for carpets and similar fabrics; and it consists in the novel grouping and configuration of figures hereinafter more fully described.

The accompanying photograph illustrates a face view of a carpet having my new design.

The ground A is filled in with small figures regularly disposed, resembling short bars crossed at both ends and arranged alternately each at right angles to the next. This ground is traversed irregularly by a loose net-work, B, of angular branching stems, bearing along their length at various intervals and in short 20 projecting stems fancifully-shaped leaf forms and conventional flower forms. The leaves

are small and serrated and irregular in form, and almost entirely right-lined and of contorted shapes. The flowers are small, and are chiefly circular gems with variously-divided centers 25 and variously attached to the stems or to each other, as more fully and exactly shown in the accompanying photograph. The design, as a whole, presents an open appearance.

I claim—

1. The design for carpets, consisting of the net-work B of flower and leaf forms, substantially as shown and described.
2. The design for carpets, consisting of the ground A and the net-work B of flower and leaf forms, substantially as shown and described.

WINTHROP L. JACOBS.
